2,435,793

CIGARETTE DISPENSER

Arthur F. Mielke, Burbank, Calif.

Application February 4, 1946, Serial No. 645,269

6 Claims. (Cl. 312—83)

1

This invention relates to cigarette dispensers. The invention is applicable either to a dispenser having a stand for use on a desk or table, or a dispenser attachable to an interior vertical surface of a motor vehicle. It is particularly useful in the latter type of dispenser, since it can be operated by one hand. Accordingly, one of the important objects of the invention is to provide a cigarette dispenser that can be operated by one hand.

The invention is directed particularly to a hopper type dispenser having a movable bottom adapted to be shifted downwardly to permit a single cigarette to issue from the hopper. This bottom is provided with a receiver extending forwardly of the forward wall of the hopper to receive a cigarette as it issues from the hopper, and to hold it in a position in which it may readily be picked up. This receiver is extended to provide a handle which the operator may engage with his finger in order to depress the hopper bottom. One of the objects of the invention is to provide a dispenser having a bottom which is informed with a cigarette receiver and with a handle which projects so as to permit the operator's finger to exert pressure against the bottom without interfering with the movement of the cigarette into the receiver.

The invention contemplates a dispenser having a hopper adapted to hold a number of cigarettes (e.g. an entire pack) and to permit only one cigarette at a time to be delivered. It is necessary to provide some means for holding back the other cigarettes during a given operation. It is also considered necessary to have some means for returning the movable bottom to the closed position after it has been depressed in order to deliver a cigarette. One of the objects of the invention is to provide relatively simple mechanism for accomplishing these functions. This is attained by the use of spring means which serve the multiple function of urging the bottom toward its closed position, of guiding the cigarettes to the ejection aperture that is defined between the forward wall of the hopper and the movable bottom when the latter is depressed, and of cutting off the passage of all except the bottom cigarette, when this aperture is exposed. It is an important object of the invention to provide a spring mechanism having this multiple function, in order to reduce the number of parts and provide a relatively simple device.

Another object is to provide a dispenser having such a spring mechanism which has the further function of agitating the cigarettes in the hopper

2

each time the bottom is depressed and returned to its closed position, in order to assure the feeding of the cigarettes to the discharge aperture and avoid clogging of the hopper.

Another object of the invention is to provide a dispenser having a spring mechanism which, in addition to the functions mentioned above, serves to retain the bottom of the hopper in assembled relation to the walls of the hopper. In this respect, the invention contemplates a dispenser in which the vertical walls of the hopper may be formed integrally of, for example, molded plastic, and in which the bottom is formed separately and has projecting hinged trunnions adapted to cooperate with the side walls of the hopper to form a hinge. Since the vertical walls of the hopper are formed in one piece, it is necessary that the hinge sockets, in which the trunnions are received, be open on one side to permit the assembly of the trunnions into these sockets. The spring mechanism when applied to the bottom, exerts spring pressure in a direction to hold the trunnions in engagement with these open sockets, and prevents the trunnions from being dislodged from the sockets under ordinary circumstances.

Another object of the invention is to provide a cigarette dispenser including a hopper mechanism which is adapted to be applied either to a stand or to a suction cup or suction cups by means of which it may be attached to a vertical surface such as, for example, the window of an automobile, or the dash thereof.

Another object of the invention is to provide a cigarette dispenser having simple means for holding a book of matches in a position in which the matches may be detached and struck, only one hand of the operator being required for this purpose.

Other objects of the invention will become apparent in the ensuing specification, taken in connection with the appended drawings, in which:

Fig. 1 is a side elevation of a cigarette dispenser embodying my invention;

Fig. 2 is a front elevation of the dispenser;

Fig. 3 is a rear elevation of the dispenser;

Fig. 4 is a vertical sectional view of the hopper portion of the dispenser taken on the line 4—4 of Fig. 1;

Fig. 5 is a vertical sectional view of the hopper portion of the dispenser taken on the line 5—5 of Fig. 4, and;

Fig. 6 is a side elevation of the dispenser applied to a vertical surface by suction cups.

As an example of one form in which the in-

vention may be embodied, I have shown in the drawings a cigarette dispenser having a hopper provided with forward, rear and side vertical walls 10, 11 and 12 respectively, and having a bottom 13 that is pivoted to the side walls 12 through the medium of trunnions 14 that are received in open, slot like sockets 15 in the side walls 12. The lower edge of the front wall 10 terminates substantially at the level of the upper sides of the sockets 15, and the bottom 13, when in its closed position, engages this lower edge of the wall 10.

The spring mechanism for holding the bottom 13 in its closed position comprises a pair of leaf springs 16 each including a tang 17 at one end, confined in a downwardly opening socket 18 in the rear wall 11. The opposite end of each spring is engaged in a depression 19 in the bottom 13, and abuts a ridge or projection 20 extending upwardly from the upper surface of the bottom 13. Between this opposite end and the tang 17, each spring is bent into the form of a V to provide downwardly and forwardly inclined guide portions 21, rearwardly extending pressure arms 22, and a separating nose 23. In their normal unstressed state the springs are positioned with the arms 21 and 22 disposed at a greater angle than the acute angle assumed in the assembled dispenser. Consequently, the pressure arms 22 exert downward pressure against the rear portion of the bottom 13 projecting rearwardly of the hinge trunnions 14. This downward pressure results in the yielding engagement of the lower edge of the wall 10 by the forward area of the bottom 13. At the same time, in the normal, unstressed state of the springs, the tangs 17 and guide portions 21 are under tension tending to move them toward the rear wall 11, and this rearward pressure, applied to the bottom 13 through the pressure arms 22 and projections 20, maintains the hinge trunnions 14 snugly in engagement with the rear extremities of the sockets 15.

The nose portions 23 of the springs are normally spaced from the front wall 10 sufficiently to permit the lowermost cigarette C to rest upon the bottom 13. At the same time, the spacing of the nose portions 23 from the wall 10 is sufficiently restricted so that the adjacent cigarette (C') will not be permitted to move down alongside the lowermost cigarette C, but will be held at a level substantially above the level of the nose portions 23. As a result, when the bottom 13 is depressed, the nose portions 23 will be moved forwardly toward the wall 10, into engagement with the cigarette C', clamping the same against the forward wall 10, before the lowermost cigarette C has been permitted to leave the hopper. The engagement of the cigarette C' takes place when the cigarette C has dropped slightly (a distance which may be approximately one-third its diameter), and this engagement will arrest downward movement of the remaining cigarettes while the cigarette C moves on out of the hopper. When the bottom 13 has been sufficiently depressed to permit the cigarette C to pass between the lower edge of the wall 10 and the bottom 13, the cigarette C will roll into the receiver hooks 24 on the forward region of the bottom 13. This position of the bottom 13 is shown in dotted lines in Fig. 5, and the forwardly projected position of the springs 16 is also shown in dotted lines. The position of the cigarette C' when it has dropped down slightly and has been engaged by the nose portions 23 is likewise shown in dotted lines.

When the bottom 13 is permitted to return to its closed position (shown in full lines in Fig. 5), the springs 16 will move away from the front wall 10 and will then permit the cigarette C' to drop down upon the bottom 13 and to assume the position of the cigarette C, the other cigarettes moving on down to fill the space above this lowermost cigarette. In thus moving downwardly, the stacked cigarettes in the hopper will be guided downwardly and forwardly by the guide portions 21 of the springs 16.

It may be noted that as the springs 16 are flexed with the lowering of the bottom 13, that the guide portions 21 will push the stacked cigarettes forwardly and upwardly, and that as the springs return to their normal positions the stacked cigarettes will be permitted to move downwardly into a widening space between the guide portions 21 and the front wall 10. This alternate shoving of the cigarettes upwardly and forwardly and permitting them to drop back downwardly and rearwardly produces an agitation which maintains the downward movement of the cigarettes and avoids congestion.

It will thus be seen that the spring members 16 have the multiple function of returning the bottom to its closed position, maintaining the bottom in assembled relation with the hopper, forming parting stops for permitting the lowermost cigarette to issue from the hopper while obstructing the escape of the remaining cigarettes, providing guide means for guiding the cigarettes downwardly and forwardly toward the discharge aperture, and agitating the cigarettes to prevent congestion.

The sockets 15 are formed in portions of the side walls 12 which project below the plane of the lower edge of the front wall 10. The rear wall 11 is projected down to the same extent, largely for the purpose of appearance.

The sockets 18 are formed in ribs 25 (integral with the rear wall 11) which form guide ways for the cigarettes above the guide portions 21 of the springs 16 and assure the feeding of the cigarettes into engagement with the guide portions 21. At the upper end of the hopper is a flange 26 that is adapted to be received in a cover or cap 27.

The receiver hooks 24 are spaced apart to permit the fingers to be inserted between them in order to readily grasp the central region of a cigarette supported between them. Each of the receiver hooks terminates in a handle 28 which extends forwardly from the trough member 24 to permit an operator to depress the bottom without blocking the movement of a cigarette into the hooks 24.

Formed integrally with the front wall 10 are a pair of match book sockets 29. The forward flanges 30 of the sockets 29, which project toward each other, are inclined downwardly and toward the wall 11 to correspond to the shape of a book of matches such as that shown at 31 in Fig. 2. The side extremities of the book 31 are received in the sockets 29, and the matches 32 project above the socket 29 so that they may easily be grasped. The abrasive surface 33 of the book 31 is exposed between the sockets 30 to permit striking a match 32.

The rear wall 11 is formed with an integral socket 34. The socket 34 is defined between a pair of ways 35, L-shaped in cross section, spaced by a slot 36. The socket is adapted to receive the shank 37 of a stand 38, or the butt portions 39 of a pair of suction cups 40. The cups 40 are

employed where it is desired to attach the dispenser to a vertical surface 41 such as the dash of an automobile. They are attached by sliding the buttons 39 upwardly into the slot 36 on the lower end thereof. The slot 36 also serves to accommodate a web member 42 on the upright 43 of the stand 38. The shank portion 37 forms a continuation of the upright 43 but is somewhat narrower so as to form shoulders 44 against which the lower ends of the ways 35 are supported.

The side flanges 45 of the bottom 13 have their ends shaped to form stops 46 that are adapted to enter slots 47 in the rear wall 11 and to engage against the upper extremities of the slots 47 to limit downward movement of the bottom 13 at the position shown in dotted lines.

I claim as my invention:

1. In a cigarette dispenser, a hopper having forward, rear and side walls; a movable bottom hinged to said hopper upon an axis intermediate the forward and rear extremities of said bottom whereby said bottom may assume a normally closed position from which the forward portion of said bottom may be moved downwardly while the rear portion thereof moves upwardly, with the downward movement of said forward portion providing an aperture through which a cigarette may issue, and a spring having an upper end anchored to said hopper, an intermediate portion projecting forwardly to provide a cigarette support and terminating in a nose normally spaced from said forward wall to form a pass through which the lowermost cigarette in the hopper may issue, and a lower portion extending downwardly and rearwardly from said nose engaged under compression against said bottom rearwardly of said hinge axis, whereby normally to yieldingly hold said bottom in said closed position, and whereby depression of said bottom will operate to move said lower spring portion upwardly and said nose forwardly to close said pass sufficiently to arrest the descent of the remaining cigarettes while permitting the lowermost cigarette to pass through said aperture.

2. A cigarette dispenser as defined in claim 1, wherein said bottom has means projecting therefrom forwardly of said forward wall and upwardly to receive a cigarette issuing from the hopper, said receiving means terminating in forwardly projecting handle means adapted to be engaged by the finger of an operator without having said finger project over said receiving means.

3. A cigarette dispenser as defined in claim 1, wherein said intermediate spring portion is inclined downwardly and forwardly so as to guide the cigarettes to said aperture.

4. A cigarette dispenser as defined in claim 1, wherein said bottom has a pair of trunnions projecting from the respective sides thereof and wherein said side walls have bayonet recesses with the terminal portions thereof extending rearwardly and downwardly, said lower spring portion exerting downward and rearward pressure against said rear bottom portion so as to hold said trunnions in said terminal portions of said recesses.

5. In a cigarette dispenser, a hopper having a forward, rear and side walls and a movable bot-

tom hinged to said side walls on an axis intermediate the forward and rear extremities of said bottom, whereby said bottom may assume a normally closed position with its forward portion in engagement with the lower edge of said forward wall and may be depressed from said position to a position spaced from said lower edge to define an aperture through which a cigarette may issue, and a spring having an upper end anchored to one of said walls, an intermediate portion projecting forwardly and having a nose normally spaced from said forward wall to form a pass through which the lowermost cigarette in the hopper may issue and having a lower portion inclined downwardly and rearwardly from said nose and engaged under compression against said bottom rearwardly of said hinge axis whereby normally to yieldingly hold said bottom in said closed position, and whereby depression of said bottom will operate to move said lower spring portion upwardly so as to move said nose forwardly to close said pass sufficiently to arrest the descent of the remaining cigarettes while permitting said bottom cigarette to pass through said aperture.

6. In a cigarette dispenser, a hopper having forward, rear and side walls; a movable bottom member hinged to said side walls on an axis intermediate the forward and rear extremities of said bottom member whereby said bottom member may tilt about said axis with the forward portion thereof moving downwardly and the rear portion thereof moving upwardly; means to restrain tilting of said bottom member in the opposite direction beyond said normally closed position; and a spring having an upper end anchored to said rear wall, a downwardly and forwardly inclined intermediate cigarette supporting portion terminating in a nose normally spaced from said forward wall just sufficiently to form a pass through which the lowermost cigarette in the hopper may issue, and having a lower portion inclined downwardly and rearwardly from said nose and engaged under compression against said bottom member rearwardly of said hinge axis so as to exert downward pressure thereagainst for yieldingly holding said bottom member in said normally closed position, and whereby depression of said bottom member against the force of said spring operates to simultaneously provide an aperture between said forward portion of the bottom member and said forward wall through which the lowermost cigarette may issue and to move said lower spring portion upwardly and said nose forwardly to close said pass sufficiently to arrest the descent of the remaining cigarettes.
